US00D866783S

(12) **United States Design Patent** (10) **Patent No.:** **US D866,783 S**
(45) **Date of Patent:** **** Nov. 12, 2019**

(54) **STIMULATION DEVICE**

(71) Applicant: **Filip Sedic**, Shanghai (CN)

(72) Inventor: **Filip Sedic**, Shanghai (CN)

(73) Assignee: **LELO Inc.**, San Jose, CA (US)

(**) Term: **15 Years**

(21) Appl. No.: **29/685,067**

(22) Filed: **Mar. 26, 2019**

Related U.S. Application Data

(63) Continuation of application No. 29/666,256, filed on Oct. 11, 2018, now Pat. No. Des. 850,644, which is a continuation of application No. 29/610,485, filed on Jul. 12, 2017, now Pat. No. Des. 835,796.

CLAIM

I claim the ornamental design for a stimulation device, as shown and described.

DESCRIPTION

FIG. 1 is a rear view of the stimulation device showing my new design.

FIG. 2 is a left side view thereof.

FIG. 3 is a front view thereof.

FIG. 4 is a right side view thereof.

FIG. 5 is a top view thereof.

FIG. 6 is a bottom view thereof.

FIG. 7 is a perspective view thereof; and,

FIG. 8 is another perspective view thereof.

The broken lines shown in the figures are for the purpose of illustrating environmental structure, which form no part of the claimed design.

1 Claim, 8 Drawing Sheets
